UNITED STATES PATENT OFFICE

140,564

DESIGN FOR A SPOON OR SIMILAR ARTICLE

Knut L. Gustafson, Chicago, Ill.

Application January 24, 1945, Serial No. 117,563

Term of patent 14 years

(Cl. D54—12)

To all whom it may concern:

Be it known that I, Knut L. Gustafson, a citizen of the United States, residing at Chicago, in the county of Cook and State of Illinois, have invented a new, original, and ornamental Design for a Spoon or Similar Article, of which the following is a specification, reference being had to the accompanying drawing forming a part thereof.

Fig. 1 is a horizontal plan view of a spoon or similar article showing my new design, and

Fig. 2 is a horizontal side view of the same.

I claim:

The ornamental design for a spoon or similar article, as shown.

KNUT L. GUSTAFSON.
